United States Patent Office.

GEORGE W. HILDRETH, OF LOCKPORT, NEW YORK.

Letters Patent No. 74,688, dated February 18, 1868.

IMPROVED SCHOOL-DESK.

The Schedule referred to in these Letters Patent and making part of the same.

TO ALL WHOM IT MAY CONCERN:

Be it known that I, GEORGE W. HILDRETH, of Lockport, in the county of Niagara, in the State of New York, have invented Improvements in School-Desks; and I do hereby declare that the following is a full and exact description thereof, reference being had to the accompanying drawings, and to the letters of reference marked thereon, which refer to the same parts in the various figures.

Figure 2 is a side elevation.

Figure 3 is a transverse section in perspective.

Figure 4 is a perspective view of a desk finished.

The nature of my invention consists in so constructing a school-desk that the iron stanchions can be fastened to the wood-work in a strong, substantial manner, (without braces,) by extending the irons up inside of the wood-work part of the desk, through mortises cut in the bottom of said desk, and screwing the irons to the sides and in the corners of said desk, getting a longer leverage hold of the wood-work, which wood-work is made in the ordinary shape of a desk, except the top or lid thereof is made in three parts, and so hung as to be turned up, or so folded as to make a book-rack, for holding the book of the scholar in a position to make him sit with ease, and in an erect position.

To enable a person to make and use my invention, I will proceed to describe its construction in detail.

Fig. 4 is a perspective view of a double desk for two scholars, with one portion of the lid or top in a position to write upon. The other portion is so folded as to make a book-rack, for holding the book in a position for reading or studying, as will also be seen in fig. 2, which shows further how the book is held to its place by the lower end of the book resting against a ledge, *a*, inside of the desk, and the book is held open by the open leaves bearing against the inside front part of the desk, as seen at *b*. The front portion of the lid *e* is placed just far enough from the front, *d*, to make room for the thickness of the book. The book at the same time holds the lid in place, and the lid holds the book in place. A notch may be cut in the end of the desk at *f*, to hold the lid open when the book is out, or a button can be placed inside of the desk, to be turned up to hold the lid open. When you wish to lower the lid for writing-purposes, &c., take out the book, turn down the button, and the lid will drop to its natural position without making a slamming noise, because the escape of the air is so slow from the end openings, thus forming a cushion to produce that effect. The dotted lines show the various positions in which the top can be placed. The ledge *g* is for holding pens or pencils safely. Fig. 3 shows how the iron stanchions are attached to the wood; *h* shows the inside front of the desk; *i* shows the further inside end of the desk. The irons are shaded darkish. The bottom of the desk, *j*, is shaded yellowish, or wood-color. The outside top and front are pink or cherry-color.

The upper ends of the irons *k* are screwed to the end *i*; *l* are screwed to the front *h*; *l* and *k* are screwed in the corner of *h* and *i*; *m* are to be screwed to the end that is left out, to get an inside view; *n* are for screws to go into the edge of the end of the desk.

The stanchions *p* may be of any desired form. The centres of the hinges on which the top or lid folds up are seen at *o*, in figs. 2 and 3, which may be of any desired pattern. The pieces forming the top of the desk may vary in width, as desired.

What I claim as my invention, and desire to secure by Letters Patent, is—

The joint *o*, in combination with the ordinary joint *s*, for the purpose of raising the central portion of the desk-lid, to form a book-rack of the desk-top or lid, as herein specified and shown.

G. W. HILDRETH.
